[57] CLAIM

The ornamental design for a displaying stand, as shown and described.

DESCRIPTION

FIG. 1 is a perspective view of a displaying stand showing my new design;

FIG. 2 is a front view thereof;

FIG. 3 is a rear view thereof;

FIG. 4 is a left side elevational view thereof;

FIG. 5 is a right side elevational view thereof; and,

FIG. 6 is a top plan view thereof.

The horizontal surfaces and center vertical pole shown in broken lines in FIGS. 1, 2, 3, 4 and 5 form no part of the claimed design.

The bottom of the displaying stand forms no part of the claimed design.
